UNITED STATES PATENT OFFICE.

LEE P. HYNES, OF CHICAGO, ILLINOIS, ASSIGNOR TO RAILWAY UTILITY COMPANY, OF CHICAGO, ILLINOIS, A CORPORATION OF ILLINOIS.

ELECTRIC CAR-HEATING SYSTEM.

1,237,341.

Specification of Letters Patent. Patented Aug. 21, 1917.

Application filed March 22, 1913. Serial No. 756,190.

To all whom it may concern:

Be it known that I, LEE P. HYNES, a citizen of the United States, residing at Chicago, county of Cook, State of Illinois, have made certain new and useful Improvements in Electric Car-Heating Systems, of which the following is a specification.

My invention relates more particularly to such a system which is thermostatically controlled, my object in part being to employ therein a thermostat thermometer for making and breaking the circuit through the car heaters. By thermostat thermometer I mean to indicate a thermostat which comprises a column of mercury which, near its lower end, is in constant contact with one branch of a circuit and is adapted to complete the circuit by making contact at a point higher up in the tube inclosing the mercury column. An instrument of this character is rather delicate and it is necessary to avoid sparking upon the completion or interruption of the circuit. My invention therefore comprises means by which the heating current can be controlled to a nicety by a thermostat of this character without risk of injury to the latter. In the accompanying drawings and in the following specification I have specifically set forth a preferred form of my invention and of the various details thereof for the purpose of exemplifying the same but it is to be understood that I am not limited to the specific system or apparatus shown but the scope of my invention is to be gathered from the following claims in which I have endeavored to define the same from the prior art so far as known to me without, however, relinquishing or abandoning any portion thereof.

In the accompanying drawings Figure 1 is a diagrammatic representation of my system; Fig. 2, a vertical section of the main relay or cutout on the line 2—2 of Fig. 3; Fig. 3, a top plan of the same with the cover removed; Fig. 4 is a fragmentary vertical section on the plane of the line 4—4 of Fig. 3 at right angles to the plane of Fig. 2; Fig. 5 is a vertical section of an auxiliary relay on the line 5—5 of Fig. 6; Fig. 6 is a top plan view; Fig. 7 is a vertical section of the same on the line 7—7 of Fig. 5; Fig. 8 is a vertical section of a shunt resistance forming part of my system; and Fig. 9 is a vertical section of a special form of thermostat thermometer likewise forming part of my system.

Each part is designated by the same character of reference wherever it occurs in the several views. Referring first to the diagrammatic view, the trolley or other supply circuit is indicated at 11—12, the car heaters at 13—13 and the circuit is closed through the latter by means of a main contactor 14 the details of which need not be described since it is or may be of a form well known in the art and which comprises 65 as diagrammatically shown in Fig. 1, a pivoted switch 15, an electro-magnet 16 controlling the same, resistances 17 and 18 connected on opposite sides of said electro-magnet, a stationary contact 19 and a blow-out 70 20. Any other form of electro-magnetically operated contactor capable of taking care of the trolley voltage which in modern practice ordinarily amounts to about 550 volts, may be employed instead of that just described. The coil of the magnet 16 together with the resistances of the main contactor form part of a circuit in shunt to the main heating circuit comprising also contacts of a cut-out or main relay 21 and wires 22 and 75 23. A second shunt circuit between the leads of the trolley, which is permanently closed, includes a wire 23', shunt resistance 24, wire 25 and wire 23 above mentioned. From the last named circuit a minor shunt circuit is 80 taken comprising the thermometer thermostat 26 and the coil of an auxiliary relay 27. In order to secure from the main circuit of 550 volts a sufficiently small voltage to avoid injury to the thermometer thermostat the 85 circuit thereof is in shunt to a small section 28 of the shunt resistance 24 and obviously by proportioning the resistance of this section 28 to the entire resistance across the leads the voltage in the thermostat circuit 90 95 may be made of any desired amount. The auxiliary relay 27 controls the current through the coil of the main relay 21, the spring 29 controlled thereby serving to close the normally open contacts 30—31 of said 100 main relay coil. The main relay 21, when energized, opens contacts in the circuit through the coil of the main contactor referred to above, and thereby breaks the heating circuit. A condenser 32 is connected 105 across the contacts 30—31 of the auxiliary relay to prevent arcing and a condenser 33 is connected across the terminals of the thermometer thermostat 26 for the same purpose when the current is broken, but the circuit 110

including condenser 33 is controlled by the main relay and is open when the contacts of the latter are closed as diagrammatically shown in Fig. 1, so that upon the making of contact by the thermometer thermostat the condenser has no effect thereon.

With this somewhat general description of the system I shall proceed to describe the various elements thereof.

As shown in Figs. 2, 3, and 4, the main relay comprises a casing 34, which may be of iron, containing a solenoid coil 35 preferably mounted upon a spool for convenience in removal and readjustment and surrounding a non-magnetic tube 36 of brass or other similar material in which the solenoid core 37 is freely movable in a vertical direction. At its lower end the casing is closed by an iron cover plate 38 and its upper end by an iron disk 39 having a depending nipple or boss 40 of the same material which is hollow and countersunk at its lower end 42 of the solenoid. The casing 34, cover plate 38, disk 39, and boss 40 form with the solenoid a substantially closed magnetic circuit. At its upper end the solenoid core is tapered at 41 and connected to a neck 43 upon the upper reduced end of which is mounted a spool or collar 44 of insulating material secured to the neck by a nut 45. Above the disk 39 is mounted an insulating disk 46 upon which are secured brackets 47-47 between the projecting ears of which are pivoted the contact levers 48-48 which are of bell crank form and control the current through the coil of magnet 16 of the main contactor. To the outer and longer arms of these levers are secured in any suitable manner, as by the metal clips 49-49, the members of a pair of carbon contact blocks 50-50 which are further secured in position by screws 51-51. The contact levers 48 are provided with inwardly projecting arms 52-52 which engage in the groove of the spool or collar 44 and are operated thereby to swing the contact arms into closed or open positions. The upper end of the casing is closed preferably by a cover 53, the under face of which is protected by a disk of insulating material; mica may be suggested as suitable for the purpose. Upon opposite sides of the pair of contact arms are mounted insulating plates 55-55, preferably of mica, 55 which are screwed or otherwise secured to blocks of insulating material 56-56 screwed to the walls of the casing. Within the segments divided off on opposite sides of the contact arms by these insulating plates are mounted electro-magnets 57-57, to the cores 58-58 of which are attached angular core pieces 59-59 which extend downwardly upon opposite sides of the contact blocks but outside the mica insulation. The coils of these electro-magnets are connected in

series with the contact arms of the device so that as long as the current is passing between the latter it is also passing through the magnets which are so wound and the cores of which are so connected to the iron plate 39 as to form a magnetic circuit, the only break of which is across the space occupied by the contact blocks. This magnetic circuit has no appreciable effect upon the contact blocks when the latter are in closed position. When, however, the circuit is opened by separating the contact blocks, the magnetic circuit exerts its well known effect to quench any arc that may be drawn between the carbons. The pole pieces of the magnets are however protected by the insulating partitions.

It will of course be understood from the foregoing description that when a current passes through the solenoid coil of the relay the core is drawn upward within the same and throws the inner ends of the contact members upward and the carbon blocks apart. By suitably proportioning the arms of each contact member a slight movement of the solenoid core will be sufficient to make the necessary gap between the carbon blocks. Obviously, from the construction a comparatively small current is sufficient to maintain the solenoid core in its upper position and the weight of the latter, when no current is passing through the solenoid coil, is sufficient to insure close contact between the carbon blocks.

As heretofore stated, this main relay not only controls the current through the magnet of the main contactor but also opens and closes the circuit through the condenser 33. The particular construction by which this is accomplished is shown in Fig. 2. The lower cover plate 38 is formed with a central aperture through which the solenoid core extends and which is tapped to receive a sleeve 60 of suitable conductive material provided intermediate its ends with a perforated diaphragm 61 and at its lower end with a closure cap threaded thereon. A plunger 63 of insulating material projects through the opening in the diaphragm 61 to an extent sufficient to permit it to be struck and moved by the solenoid core in its descent and is normally held in an elevated position by a spring 64 compressed between the cap 62 and the cupped lower end of the plunger. Upon the shoulder 65 of the plunger is mounted a brass ring 66, having contact points 67 for making electrical connection with the diaphragm 61. One branch of the circuit of condenser 33 is attached to the brass ring through an opening 68 in the plunger, and other branch of the circuit to the sleeve at 69. When the solenoid core is in its lower position, as it is when current is flowing through the contacts, the magnet of the main contactor and

the heating circuit, it holds the plunger with its contacts away from the diaphragm 61 and the circuit of condenser 33 open; and it is while these parts are in this condition that the heaters raise the temperature of the apartment in which the thermometer thermostat is located until ultimately the mercury bridges the contacts of the latter. When, however, following the attainment of the desired temperature, the auxiliary relay 10 closes the circuit through the coil of the main relay, the solenoid core is raised and completes the condenser circuit by allowing the spring to force the plunger against the 15 diaphragm.

The condensers 32-33 are or may be of any ordinary approved type but the auxiliary relay 27 and the shunt resistance present features of novelty in their construction and will be specifically described.

The relay as shown in Figs. 5, 6, and 7, comprises a case, preferably of sheet metal, in which is inclosed a solenoid coil 27, the core 72 of which is limited in its movement 25 by screws 73-73 extending through openings in the armature plate 74 of the core. Screws 73 are attached into a U-shaped iron forging 75 which partially surrounds the solenoid coil, and the ends 76 of which 30 extend beneath the coil to form with the armature plate and core a substantially closed magnetic circuit. Above the forging 75 the casing is substantially closed by a disk 77 of insulating material upon which 35 is mounted a leaf spring contact 31. The disk 77 and forging 75 are perforated in the axis of the solenoid coil and core, and the latter carries a rod 30 of insulating material which is adapted when the solenoid core is drawn upward, to bear against the spring contact 31 and close it against the adjustable stationary contact 30 which, as shown, comprises a screw mounted in a bracket 80, the latter being connected to the 40 terminal of the main relay and the spring contact being connected to the wire 22, as shown at 81. The specific construction of the shunt resistance 24 diagrammatically shown in Fig. 1, is illustrated in Fig. 8. It 45 comprises a nonmagnetic casing 82 which is adapted to be screwed to any flat surface and incloses a spool 83, through the bore of which a screwbolt 84 for the purpose of securing it to a support 85, by means of the nut 86. Upon the spool is a coil of suitable 50 resistance material, the terminals of which are connected by wires T, R to the wires 23', 25, respectively. At an intermediate point between the ends of the coil and preferably toward the middle thereof, a suitable length of the resistance material is shunted 55 through the thermometer thermostat circuit by the wires 87-88. The current through the thermometer thermostat will of course be determined by the fall potential across

these terminals, and the latter may be substantially fixed by determining the total fall of potential in the resistance coil and properly proportioning the shunted length of the coil. By connecting the shunt near the center of the resistance coil the danger of disastrous short circuiting is avoided. As above stated, a construction of the thermometer thermostat is shown in Fig. 9. This device comprises a thermometer tube 75 80 of glass or similar insulating material in which the bore is enlarged as at 90-91 at the point where the contact wires are inserted, for the purpose of securing a larger contact surface. In the particular form shown but two contacts are employed, but it will be understood that if desired, a number of contacts to be alternatively employed, may be inserted in the thermometer tube, and suitably connected. The wires forming 85 the contacts 92-93 are preferably of platinum and extend through bores or openings formed in the wall of the tube and into the enlarged openings or cavities above mentioned, and turn downward to the lower ends thereof, and are suitably covered with insulating material from the points at which they enter the thermometer tube. As shown in the figure, the wires are bent to lie against the outer wall of the thermometer 90 tube and wrapped with wire or cord, as at 94-95, to prevent their being broken. The thermometer tube is incased throughout its length from the bulb upward in a housing 95 100 of rubber, glass, or similar insulating material, which fits closely around the tube immediately above the bulb and is filled with an insulating compound which is poured in around the thermometer and allowed to set. The insulator tube is incased in a tubular metal jacket 97 which 105 also extends over and protects the bulb and is closed at its upper and lower ends by screw plugs 98-99 forming parts of brackets 100-101, adapted to be attached 110 to a wall or other flat surface, the walls of the jacket being perforated opposite the bulb to allow free contact with the air.

The particular arrangement of the various elements of the system is of course immaterial, so long as the connections above described are provided, but it is ordinarily found convenient to inclose the main relay or shunt resistance and the auxiliary relay in a suitable case or box, and to mount 115 the thermometer thermostat where it will be exposed to the air in the compartment to be heated, and under observation.

The operation of the apparatus has been substantially described in connection with the detailed description, but a consecutive statement thereof at this point may be briefly made, as follows: The wires 11-12 being connected to the trolley or other source of electrical energy, if the temperature is 120 125 130

below that for which the thermometer thermostat is arranged or set, there will be no current through the latter, the auxiliary relay will be unenergized and its contacts open, there will be no current through the coil of the main relay and hence its contacts will be together, permitting a flow of current through the coil of the main contactor, closing and retaining closed the switch thereof, which closes the circuit through the car heaters. When the temperature in the car or other compartment being heated rises sufficiently to cause the mercury in the thermometer thermostat to close the circuit therethrough, the current flows from the shunt of resistance 24 through the thermometer thermostat and a coil of the auxiliary relay 27. It may be noted here, as above described, the circuit of condenser 33 being open at the main relay at the time the contact is made at the thermometer thermostat, the condenser is inactive and no discharge spark is given. The flow of current through the coil of the auxiliary relay attracts the core and armature thereof, drawing them up into position in which the insulator rod 79 closes the contacts of the switch. This closes a circuit from the conductor 23' through the coil 21 of the main relay, contacts 30-31, wires 22-23, back to line. The main relay thereupon draws up its armature and throws open the contacts controlled thereby, as heretofore described and if an arc is formed between said contacts, it is immediately blown out by the magnetic circuit above described. The opening of the contacts of the main relay breaks the circuit through the coil 16 of the main conductor, the switch whereof immediately opens and the current through the heaters is interrupted. When the temperature in the compartment falls so as to open, the circuit at the thermometer thermostat, the condenser 33 is in shunt therewith, and prevents sparking. At the same time the auxiliary relay is energized to open the circuit through the main relay coil, thereby permitting the contacts of the main relay to close, completing a circuit through the main conductor coil and causing it to close the main conductor switch.

I claim:

1. In an electric system for heating cars and the like, a heating circuit, a main contactor for controlling said circuit, comprising an electro-magnetic operating coil, a main relay controlling the current through said coil, and comprising an operating coil, an auxiliary relay controlling the current through the latter coil, and comprising an operating coil and a thermostat controlling the current through the last named coil.

2. In a heating system of the class described, a heating circuit, electro-magnetic means for opening and closing the same,

said means including a thermostat adapted and arranged to make and break the current through said electro-magnetic means, a condenser in shunt to said thermostat, and means for closing the condenser circuit after the circuit is closed through said thermostat, and opening it after the circuit through the thermostat is open.

70

3. In a heating system of the class described, and in combination with the heating circuit and electro-magnetic means for opening and closing the same, a main relay controlling the flow of current through said electro-magnetic means and including an electro-magnetic coil and a part operated thereby, a thermostat controlling the passage of current through the main relay and a condenser in shunt to said thermostat, the circuit of which comprises a pair of contacts controlled by the movable part of the main relay.

75

4. In a heating system of the class described, and in combination with the heating circuit and electro-magnetic means for opening and closing the same, a main relay adapted to open and close the circuit through said electro-magnetic means, an auxiliary relay for controlling the circuit of the main relay and comprising an electro-magnetic coil, a thermostat controlling the circuit of the auxiliary relay, a condenser in shunt to said thermostat, and connections controlled by the main relay for opening and closing the condenser circuit.

90

5. In a heating system of the class described, and in combination with the heating circuit and electro-magnetic means for opening and closing the same, an auxiliary relay controlling the current through said electro-magnetic means, a thermostat controlling the circuit through the relay, a condenser in shunt to the thermostat, a pair of contacts controlling the condenser circuit, and means operated by the main relay for controlling the said contacts.

100

6. In a heating system of the class described, and in combination with the heating circuit thereof and its electro-magnetic contactor, a permanently closed circuit in shunt thereto, and comprising a resistance, a circuit in shunt to a section of said resistance and comprising a thermostatic switch and electro-magnetic means for controlling the operation of said main contactor.

105

7. In a heating system of the class described, and in combination with the heating circuit and its electro-magnetically controlled contactor, a permanently closed shunt to said heat circuit comprising a resistance, a main relay controlling the current through said contactor, a thermostatic contact device and an auxiliary relay, the electro-magnetic coil of which is in shunt to a section of the resistance, contact means controlled by said auxiliary relay; for con-

110

115

120

- trolling the passage of current through the main relay, and means controlled by the main relay for controlling the passage of current through the contactor.
- 5 8. In a heating system of the class described, and in combination with the heating circuit and the electro-magnetic contactor thereof, a main relay, the contacts of which are comprised in and control the circuit of the contactor, a pair of contacts controlling the electro-magnetic means of the main relay, a permanently closed circuit in shunt to the heating circuit and comprising a resistance, a circuit in shunt to a section 10 of said resistance, and including a thermostatic switch and electro-magnetic means controlling the last mentioned contacts.
9. In a heating system of the class described and in combination with the heating circuit 20 thereof an electro-magnetic switch controlling the heating circuit, a main relay comprising a solenoid coil, core, and contacts, the latter of which control the passage of current through the first named switch, a 25 pair of contacts for making and breaking circuit through said solenoid coil, a perma-

nent shunt to the heating circuit comprising a resistance, a circuit in shunt to a portion of said resistance and including a thermostatic contact and electro-magnetic means 30 controlling the contacts in the main relay coil circuit.

10. In a heating system of the class described, and in combination with the heating circuit and an electro-magnetic contactor 35 controlling the same comprising an electro-magnetic coil 16, a main relay 21, the contacts of which control the passage of current through the electro-magnetic switch, a pair of contacts 30-31 controlling the passage of 40 current through the main relay, an electro-magnetic means 27 for controlling the last named contacts, a resistance 24 in shunt to the heating circuit, and a circuit comprising the electro-magnetic means 27 and the thermostat 26 in shunt to a section of said resistance. 45
